UNITED STATES PATENT OFFICE.

WALTER H. BURNHAM AND JOHN E. FLOYD, OF CHICAGO, ILLINOIS; SAID FLOYD
ASSIGNOR TO SAID BURNHAM.

LAUNDRY CONVEYER.

Application filed February 28, 1927. Serial No. 171,439.

In laundries the manglers are required to handle different classes of articles some of which are heavier in weight and require re-ironing to properly dry the same. The manglers are set to run at a speed sufficient to properly iron the average run of pieces, but when heavier pieces put through a mangle are deposited on the receiving table they may readily be selected for return to 5 the feeding end of a mangle for reironing.

This invention relates to an improved type of conveyer mechanism or go back carrier for use in laundries in combination with a mangle or ironer whereby an attendant at 15 the discharge end of the machine may sort and place partially ironed pieces in the conveyer for return to the attendant at the feeding end of the machine for reironing, without making it necessary for the attendant at 20 the discharge end of the machine to leave the same.

It is an object of this invention to provide an improved conveyer for use in combination with a mangle or ironer to permit 25 partially dried pieces to be conveniently returned to an attendant at the feeding end of the machine for reironing.

It is also an object of this invention to provide an ironer with a conveyer mechanism to permit an attendant at the discharge 30 end of the ironer to place improperly dried pieces in a conveyer adapted to convey said pieces into a receiving bag positioned adjacent the machine at the feeding operators' 35 station and having a suitable opening therein, permitting an attendant at the feeding end of the machine to remove the improperly dried pieces from the bag and again feed the same into the ironer for reironing.

40 It is an important object of this invention to provide a laundry mangle or ironer with a conveyer mechanism at one side of the machine positioned to permit an attendant or folder at the discharge end of the ironer 45 to sort ironed goods and deposit improperly dried pieces into one end of a conveyer which acts to automatically convey such pieces of goods upwardly to be deposited into the upper end of an adjustable bag or container from which the improperly dried pieces may be removed at intervals to permit a feeder attendant at the feeding end of the ironer to again feed said pieces into the ironer for reironing.

50 Other and further important objects of

this invention will be apparent from the disclosures in the specification and the accompanying drawings.

This invention (in a preferred form) is illustrated in the drawings and hereinafter 60 more fully described.

On the drawings:

Figure 1 is a side elevation of an improved conveyer embodying the principles of this invention shown associated with a 65 laundry ironer illustrated in a schematic form.

Figure 2 is an enlarged vertical detail section taken on line II—II of Figure 1.

Figure 3 is a fragmentary inner side elevation of one end of the conveyer mechanism taken on line III—III of Figure 2.

Figure 4 is a top plan view of the conveyer mechanism illustrated in Figure 1.

Figure 5 is a fragmentary side elevation 75 al view taken on line V—V of Figure 4.

Figure 6 is a fragmentary longitudinal section of the lower end of the conveyer taken on line VI—VI of Figure 4.

Figure 7 is a transverse section of the conveyer taken on line VII—VII of Figure 1.

Figure 8 is a lower end view of the conveyer taken on line VIII—VIII of Figure 1.

Figure 9 is a transverse fragmentary detail section taken on line IX—IX of Fig- 85 ure 5.

Figure 10 is a transverse section of the bag taken on line X—X of Figure 2.

As shown on the drawings:

The reference numeral 1 indicates as a 90 whole a laundry mangle or ironer of any desired type or construction having a laundry receiving counter or table 2 positioned across the discharge end of the ironer in a convenient position to permit an attendant 95 at the discharge end of the machine to receive, sort and fold the ironed pieces of laundry as they come from the ironer. To permit the pieces of laundry which are not properly dried to be returned to the attendant at the feeding end of the ironer an improved conveyer mechanism is provided positioned at one side of the machine having one end easily accessible by the attendant at the discharge end of the machine while the other end is positioned convenient for access by an attendant at the feeding end of the machine.

The improved mechanism of this invention is adjustably supported by ropes or cables 110

3 each carrying a bail or yoke 4. The upper bail 4 has the ends thereof securely fastened to the opposite sides of a three sided box or container 5 into the open side of which the 5 upper end of two parallel chute side boards 6 project. The upper ends of the chute side boards 6 are supported by means of brackets 7 connected to the bearing supports 8 of an upper conveyer roll 9. Mounted on one end 10 of the shaft of the upper conveyer roller 9 is a grooved sheave or pulley 10 around which an endless driving belt 11 is trained. The endless driving belt is also engaged around a sheave or small pulley 12 supported on one 15 end of a transverse auxiliary shaft 13 which projects across the top of the conveyer chute and is journaled in suitable bearing brackets 14 secured to the chute side boards 6. Engaged on the opposite end of the trans- 20 verse shaft 13 is a sheave or pulley 15 around which an endless driving belt 16 is trained. The belt 16 is also trained around a sheave or pulley 17 mounted on one end of the shaft of a driving motor 18. The motor 18 25 is secured upon a supporting bracket 19 secured to the upper ends of the chute side boards 6.

Securely mounted on the outer side of each of the chute side boards 6 are a plurality of 30 brackets 20 the lower ends of which have integrally formed thereon an inwardly directed arm 21 provided with a notch at 22 (Figure 7). The two opposite arms 21 are connected by a transverse bar 23 which connects 35 the two brackets and affords a support for a chute floor or bottom board 24. The arms 21 and the cross bar 23 hold the bottom board 24 in position spaced from the lower edges of the two side boards 6. It will thus 40 be seen that the chute comprises the two side boards 6 and the bottom board 24 which is spaced from the lower edges of said side boards to afford longitudinal slots or openings 25 which extend substantially the entire 45 length of the chute.

These slots or openings are provided to prevent articles carried by the conveyer from becoming caught or pinched beneath the side boards and said conveyer.

50 Positioned adjacent the outer side of the lower end of each of the side boards 6 is a bearing bracket 26 which projects downwardly below the bottom board 24. Journaled in the two bearing brackets 26 is a lower conveyer roller 27. Integrally formed or rigidly secured to each of the bearing brackets 26 is a shield or guard 28 having a curved inner edge 29. The two guards 28 are positioned with the curved edges 29 op- 55 posite one another to afford a guide space permitting articles to be conveniently directed within the lower end of the chute upon an endless conveyer belt 30. The endless conveyer belt may be made of canvass or any 60 other suitable material, and passes over the

upper feed roller 9 into the chute above the bottom board 24 with the lower bight of said conveyer 30 passing around the lower roller 27 behind the shields or guards 28 and then passing upwardly beneath the chute bottom board 24 over an idler roller 31 journaled transversely beneath the chute in suitable brackets 32 fastened to the outer sides of the chute side boards 6.

70 For the purpose of adjusting the tension of the endless conveyer 30 each of the brackets 26 is provided with a pair of parallel slots 33 through which set screws or locking bolts 34 engage to hold the brackets 26 rigidly secured in a set position adjacent a U-shaped supporting bracket 35 one of which is secured on the outer side of the lower portion of each of the chute side boards 6 (Figure 5). Also secured on each of the brackets 26 is an internally threaded nut or block 36 through which an adjusting screw 37 is threaded. When the set screws 34 are loosened the adjusting screw or bolt 37 is adapted to be rotated to move the respective bracket upwardly or downwardly either to loosen or tighten the belt 30, as desired. The adjusting screw 37 is supported in the outwardly directed flanges 38 of the bracket 35.

90 Pieces of laundry or other articles deposited in the lower end of the chute upon the endless conveyor 30 are adapted to be conducted upwardly and discharged over the upper end of the conveyer into the box or hopper 5. The bottom of the hopper 5 is open to permit the 100 articles to drop therethrough into a spout, bag, or receptacle 39 constructed of canvas or any other suitable material. The bag 39 is substantially rectangular in shape having four sides, the upper edges of which are 105 provided with eyelets or any other suitable means whereby the bag may be removably secured to the lower edge of the hopper or box 5. The lower end of the bag 39 is closed by means of a wooden bottom or floor 40. One side 41 of the bag is provided with an 110 opening 42 at its lower end to permit articles to be readily taken from the bag (Figure 3). Connected to two opposite side walls of the bag are a plurality of shirr 115 strings 43 which project through eyelets or suitable openings in the bag wall 41 to permit two opposite sides of the wall to be shirred or plaited, as at 44, to cause the upper portion of the bag wall 41 to assume an inclined position to afford a guide wall or baffle 45 in the upper portion of the bag adapted to direct the articles being deposited in said bag downwardly toward the lower rear corner of the bag in a convenient 120 position for removal through the opening 42. The shirring of the bag by the strings 43 serves to position the bottom 40 of the bag in an inclined position, as clearly 125 illustrated in Figure 2, thereby tending to 130

retain the articles in the lower rear portion of the bag so that said articles will not drop out of the opening 42. The apertured wall 41 of the bag is positioned to face one end 5 of the mangle or ironer 1 and has attached to one edge thereof one end of a cord 46, the other end of which is adapted to be engaged across the outer face of the bag wall 41 to permit the lower end of the cord 46 to be engaged in an eyelet or ring 47 attached to an opposite edge of said bag. The cord 46 may be tied to cause the bag to assume a slightly inclined position with respect to the side of the mangle or ironer 1, as shown in dotted 10 lines in Figure 4. This turning of the bag positions the opening 42 near the lower end thereof in a more convenient place to permit an attendant at the feeding end of the mangle to withdraw articles from the 15 bag.

The operation is as follows:

The pieces of laundry or articles to be ironed are delivered to the feeding end of the mangle or ironer 1 where an attendant 20 is adapted to feed the articles into the mangle. The articles as they are conducted through the mangle are ironed by the rolls and are finally delivered through the discharge end of the machine onto the receiving table 2. A second attendant or folder 25 is positioned at the table 2 and as the ironed articles are delivered on said table inspects said articles to see that they are properly dried. When a piece of laundry or an article 30 is discovered which is not properly dried the attendant separates said articles from those that are thoroughly dried and deposits the same in the open lower end of the chute upon the endless conveyer 30. The guards 28 which cover the ends of the lower conveyer feed roller 27 prevent the article from coming in contact with the roller so that any trailing ends of the article will not become tangled or caught between the roller 40 and the brackets 26. The inclined edges 29 of the guards 28 form the upper ends of the guards 28 into fingers 28a which project upwardly into the chute a short distance to close a portion of the slots 25 and serve to 45 afford a suitable guideway for the articles delivered upon the conveyer 30 so that said articles are permitted to be pulled upwardly into the chute between the side boards 6 with the advance of the conveyer belt 30 50 without any danger of the articles projecting through said slots and becoming tangled with the lower roller.

The articles which are deposited upon the endless conveyer belt 30 are thus conveyed upwardly through the chute and are discharged over the upper end of the conveyer belt into the hopper or box 5, permitting the articles to drop into the bag 39 against the inclined baffle wall or apron (Figure 2) 55 which tends to direct the articles down-

wardly toward the rear wall of the bag and into the lower rear portion, thereby obviating any tendency for the articles to find their way out of the opening 42. The inclined baffle wall 45 is formed by shirring 70 two opposite sides of the bag by means of the four shirr strings 43, as clearly illustrated in Figures 2 and 3. The shirring of two of the side walls also acts to incline the bottom 40 of the bag to form a pocket in the lower rear end of the bag for the articles deposited therein. To conveniently tilt or turn the bag 39 the cord 46 may be tightened so that the opening 42 is slightly turned at 75 an angle with respect to the side of the mangle 1 so that the attendant at the feeding end of the mangle may more conveniently reach into the opening 42 to remove the articles or pieces of laundry from the bag so that they may again be fed through the 80 mangle to be reironed.

By providing a mangle or ironer with an improved conveyer mechanism of the type described a convenient arrangement is afforded for rapidly delivering improperly dried pieces of laundry from the discharge end of the mangle back to the feeding end without requiring the attendant at the discharge end to leave her position. This arrangement, furthermore, provides a considerable saving of time due to the fact that the attendant need not collect the improperly dried articles and then leave the discharge end of the machine to carry said articles around to the feeding end of the machine. 90 With the improved conveyer mechanism the work in a laundry can be done more efficiently and at a considerable saving. In case the conveyer mechanism is not needed the same may be pulled upwardly toward 95 the ceiling by means of the supporting cables 3 which also afford a means for adjusting the position of the chute with respect to the box or hopper 5 so that the chute may assume any desired inclination. If desired 100 the conveyer mechanism when raised may be pivoted or swung about its upper support into an out of the way position to permit convenient access to the ironer when necessary.

We are aware that many changes may be made, and numerous details of construction may be varied through a wide range without departing from the principles of this invention, and we therefore do not purpose 110 limiting the patent granted hereon, otherwise than necessitated by the prior art.

We claim as our invention:

1. The combination with an adjustable chute, of means for adjustably supporting said chute, a conveyer passing through said chute, means for operating said conveyer, a hopper positioned at the upper end of the chute adapted to receive articles from said conveyer, a container suspended from said 125

hopper and having an opening therein to permit the articles deposited therein to be removed, and means for tilting the bottom of said container to hold articles from falling out of said opening.

2. The combination with a chute, of means for adjustably supporting said chute in an inclined position, a hopper into which the upper end of said chute projects, means for adjustably supporting said hopper, an endless conveyer passing through said chute, means for adjusting said conveyer, a driving means for operating said conveyer to cause articles deposited on the lower end thereof to be conducted upwardly through said chute to be deposited in said hopper, a bag removably supported on the lower end of said hopper and having an opening therein to permit articles deposited in said bag to be removed therefrom, and means for shirring portions of said bag to facilitate removing articles from said bag through said opening.

3. The combination with a chute, of a hopper at the upper end of said chute, adjustable supporting means connected with said chute and hopper, an endless conveyer passing through said chute, adjustable means for tensioning said endless conveyer, driving means supported on said chute for operating said conveyer to cause articles deposited in the lower end of said chute to be conveyed upwardly and deposited into said hopper, a bag secured to said hopper and having an opening near the lower end thereof, means for shirring said bag to cause articles deposited therein to be directed downwardly into the rear portion of said bag away from said opening into a convenient position to be withdrawn through said opening, and adjustable means connected with said bag to permit the bag to be slightly twisted to conveniently position said opening for easy access thereto.

4. A laundry conveyer mechanism comprising a chute, a hopper at the upper end thereof, adjustable means for supporting said chute and hopper, an endless conveyer adapted to travel through said chute, means for tensioning said conveyer, a driving mechanism connected to operate said conveyer to cause articles deposited in said chute to be carried upwardly and discharged into said hopper, a flexible bag engaged on the lower end of said hopper to receive articles therefrom, said bag having an outlet opening therein, means for shirring a portion of said bag to cause a portion of one of the walls thereof to serve as a baffle for directing the articles delivered into said bag downwardly toward the rear portion thereof, and means for slightly turning said shirred bag with respect to the hopper to position the opening in said bag to permit

convenient removal of an article through said opening.

5. A laundry conveyer mechanism comprising a chute, a hopper at the upper end thereof, adjustable supporting means connected to said chute and hopper, a conveyer supported on said chute, means for operating the conveyer to deliver articles into said hopper, means for adjusting said conveyer, a flexible bag supported on said hopper and having an opening therein, a stiff bottom for said bag, and means for shirring said bag to tilt said bottom and form one of the walls of said bag into an inclined guide for conducting articles received from said hopper downwardly into the rear portion of said bag upon said inclined bottom.

6. A laundry conveyer mechanism comprising a hopper, a chute projecting into said hopper, conveyer means carried by said chute adapted to deliver articles into said hopper, an apertured bag suspended from said hopper, and means engaged on said bag to permit the same to be twisted with respect to said hopper.

7. A laundry conveyer mechanism comprising a hopper, adjustable means for conveying articles into said hopper, a flexible bag suspended from said hopper adapted to receive articles therefrom, means for shirring a portion of said bag to restrict the opening in said bag to guide articles therethrough, and means connected with said bag to permit the lower end thereof to be twisted with respect to the upper end thereof.

8. A laundry conveyer mechanism comprising a hopper, means for delivering articles into said hopper, a flexible bag suspended from said hopper and having an opening in the lower portion of one of the side walls thereof, a stiff bottom in said bag, a plurality of shirr strings connected to said bag to permit a portion of said bag to be shirred to afford a guide for directing articles into the lower rear portion of said bag upon said bottom, and adjustable means connected across one side of said bag adapted to hold said bag in a twisted position.

9. A laundry conveyer mechanism comprising a chute, a bag suspended from one end thereof, means for conveying articles through said chute for delivery into said bag, and means carried by said bag to permit the same to be held in a twisted position.

10. A laundry conveyer mechanism comprising a chute, means for supporting the same, a flexible container carried by said chute, means in said chute for delivering articles into said container, means connected with said container for shirring a portion thereof to restrict the opening through said container to guide articles into a portion of

the lower end thereof, and means for slightly twisting said container with respect to said chute.

11. The combination with a conveyer mechanism, of a container suspended thereon to receive articles therefrom, said container having an outlet opening therein, and means connected with said container for shirring a portion thereof to guide the articles delivered into said container into the lower rear portion of said container away from said opening.

12. The combination with an adjustable conveyer, of a container supported thereon and having an opening in one of the walls thereof, means connected with said container for restricting the passage therethrough to cause the articles delivered into the container to be directed downwardly away from said opening, and means connected with said container adapted to be adjusted to twist the lower end of said container with respect to the upper end thereof to position said opening in a more convenient location.

13. A laundry conveyer mechanism comprising a chute having longitudinal openings between the side walls and the bottom, an endless conveyer operating in said chute and projecting into said openings, means for actuating said conveyer to conduct articles through said chute, a container supported on said chute adapted to receive articles therefrom, and means for adjusting said

14. A laundry conveyer mechanism comprising a chute having longitudinal slots

between the side walls and the bottom of said chute, rollers supported below said chute, an endless conveyer belt supported on said rollers and passing through said chute above said bottom with the margins of said belt projecting into said slots, means for operating said endless conveyer belt to convey articles through said chute, mechanisms mounted on said chute for varying the tension of said conveyer belt, a hopper at one end of said chute for receiving articles therefrom, adjustable supporting means connected with said hopper and with said chute, a flexible container supported on said hopper and having an opening in one of the walls thereof, a stiff bottom secured in the lower end of said container to close the same, a plurality of shirr strings connected to certain of the walls of said container to permit a portion of said container to be shirred to restrict the passage therethrough and tilt said bottom, and adjustable means connecting two edges of said container and adapted to be set to twist the lower end of said container with respect to the upper end thereof.

15. The combination with an adjustable conveyer, of an adjustable container supported thereon to receive articles therefrom, and means for shirring said container to hold the bottom thereof in an inclined position to retain articles within the container.

In testimony whereof, we have hereunto subscribed our names at Chicago, Cook County, Illinois.

WALTER H. BURNHAM.

JOHN E. FLOYD.
